UNITED STATES PATENT OFFICE

ANDREAS GULBRANDSEN HOVDE, OF HÖNEFOS, NORWAY.

STRIKING-TRAIN FOR CLOCKS.

SPECIFICATION forming part of Letters Patent No. 316,364, dated April 21, 1885.

Application filed November 15, 1883. (Model.) Patented in Germany August 7, 1883, No. 26,886.

To all whom it may concern:

Be it known that I, ANDREAS GULBRANDSEN HOVDE, of Hönefoss, Norway, have invented certain new and useful Improvements 5 in Striking-Trains for Clocks, (for which I obtained a patent in Germany, numbered 26,886, dated August 7, 1883;) and I do hereby declare the following to be a full, clear, and exact description of the invention, such as will enable 10 others skilled in the art to which it appertains to make and use the same.

My invention relates to an improvement in clocks, the object being to provide a striking-train which shall be adjustable to all kinds 15 of clocks, and shall be of more simple construction than those hitherto known.

With these ends in view my invention consists, first, in such an arrangement of the striking-train and center arbor with respect to 20 each other that the former is wound up by means of one of the wheels of the latter—viz., by means of the same motive power (springs, 25 weights, or other arrangements) which sets the hands in motion—thereby dispensing with a whole series of wheels and other mechanism; secondly, in a new mechanism for the striking-train, which not only reduces the loss of power occasioned by doing away with the independent striking-train to a minimum, 30 but also gains an important amount of power, and is more simple in structure than those hitherto made; thirdly, in such an arrangement of the striking-train mechanism that the work performed by the winding-up part of 35 the same is equally divided throughout the whole day; and, fourthly, in a striking-train so constructed as to afford economy in space.

My invention further consists in certain features of construction and combinations of 40 parts, as will be more fully described, and pointed out in the claims.

In the accompanying drawings, Figure 1 is a front view in elevation of the striking-train and the actuating mechanism immediately connected therewith. Fig. 1^a is a front view in elevation of the striking-train and a portion of the center arbor embodying my invention. Figs. 1^b and 1^c are enlarged views of parts of same. Fig. 1^d represents the position of the wheels when the clock is about to strike one. Figs. 2^a and 2^b represent a modification, and Figs. 3^a, 3^b, and 3^c represent a

second modification; and Fig. 4 is a view in side elevation of wheel *r* and adjacent parts.

The striking-train consists, essentially, of 55 three principal parts—first, the winding mechanism; second, the movement, and, third, the regulating mechanism.

The striking-train represented in Fig. 1 is wound up by means of the pinion *l* mounted 60 on the axle of the center wheel. The pinion *l*, which makes one revolution every hour, engages the teeth of the wheel *r*, actuated toward the right by a spring, *r*⁵, (represented by dotted lines in Fig. 1^a,) and turns it to the 65 left. The pinion *l* is a mutilated fourteen-toothed wheel, a space of two adjacent teeth being vacant. The spring-actuated wheel *r* is therefore turned thirteen teeth for every 70 complete revolution of the pinion *l*. Since, however, the pinion *l* makes one revolution every hour, the recess caused by the absence of the two teeth will face the spring-actuated wheel *r* every hour, and this wheel *r* being 75 now disengaged is permitted to recede to the right, which it does, owing to the spring or weight connected with its axle.

The movement comprises the hammer *b*, mounted on the hammer-axle *a*, balanced by a counter-weight, *b'*, and continuously drawn 80 to the right against the pin *o* by means of a very delicate spring, *o'*. Furthermore, the small pinion *d*, provided with two inclined teeth, *d'* and *d''*, is loosely mounted on the hammer-axle and pressed by means of a small 85 spring, *k'*, against the pin or notch *s'* on the disk *s*. This disk *s* is firmly fixed on the axle *a*.

h is the escapement-lever, pivoted at its lower end, and provided with the two branches *h*² and *h*³ and a notch or leaf, *h'*. *h* is the bell. 90

In the position represented by Fig. 1^b the hammer has just struck, and the small lug *s*², at the lower part of the disk *s*, has just come in contact with the branch *h*³, by which the escapement-lever has been pressed to the left, 95 disengaging the leaf *h'* and thereby the wheel *r*. The wheel *r* now engages the tooth *d'* of the pinion *d*, and thereby turns the hammer-axle and hammer to the left. If, now, the wheel *r* continues to turn to the right, it will 100 engage the tooth *d''* of the pinion *d*. The lug *s*² will now press against the branch *h*², which causes the leaf *h'* to engage the tooth *r'* of the wheel *r*. This causes the arrest of the

spring-actuated wheel r in the position required to allow the teeth d' and d'' of the pinion d to pass between the teeth of the wheel r back to the position which they occupied 5 when the tooth d'' of the pinion d was engaged by the wheel r . Owing to the impetus received from the spring-wheel r , the hammer first swings to the left as far as the spring at its axle allows, or until the lug s' engages the 10 branch h' , which allows the hammer to swing to the right and strike the bell. The lug s' again disengages the escapement and another stroke follows in the same manner, as just described. The striking will continue until the spring- 15 actuated wheel r is arrested by the regulating mechanism, which will be hereinafter described. The pinion d is loosely mounted on the hammer-axle a , to allow the teeth of the wheel r to pass when it is wound up. The 20 pinion d consequently works similar to a ratchet, and may be arranged in a similar manner, as hereinafter set forth.

It will be observed that in the movement above described one stroke on the bell corresponds to two teeth on the spring-actuated wheel r . The regulating of the striking-train is accomplished as follows: Fig. 1 represents the position of the mechanism after the clock has just struck twelve. The lever f , pivoted 25 at one end, rests with the tooth f'' on the highest point of the heart-wheel m . This heart-wheel m is mounted on the axle of the center wheel, and by means of suitable gear (not shown) is caused to make one revolution every twelve hours. The tooth f' , on the left end of the lever f , presses against the step XII 30 of the snail n . The snail n is secured to the spring-actuated wheel r , and is provided with six more steps, XI to VI, inclusive, which 35 are so arranged with reference to the heart-wheel that after one-twelfth of a rotation of the heart-wheel, corresponding to one hour, the end f' has descended one step, or during the second half of the rotation has ascended 40 one step on the snail n . During the first hour the wheel r is turned a distance of thirteen teeth to the left by the pinion l , mounted on the center wheel-axle and making one revolution every hour. At the same time the 45 tooth f'' descends so much that f' occupies the same height as step XI, as shown in Fig. 1^a, and as the distance from step XII to step XI corresponds to the distance of eleven teeth of the wheel r , it will be seen that the wheel r , 50 being now disengaged, is permitted to rotate to the right a distance of two teeth only. The clock, therefore, will strike one. As the distances between the following steps of the snail n correspond to 9, 7, 5, 3, and 1 teeth of the 55 spring-actuated wheel, and as the snail is so arranged that f' at the end of each succeeding hour shall rest at the height of the notches XI X IX VIII VII VI in the declining order during the first half-revolution of the heart-wheel and in the reverse or ascending order 60 during the second half-revolution of the heart-wheel, and as the pinion l makes a complete 65

revolution each hour or for each step on the snail, thereby turning the wheel r thirteen teeth to the left, the wheel r , when disengaged 70 at the end of each hour, will be allowed to turn to the right the number of teeth corresponding to the difference between 13 and 9=4, 13 and 7=6, 13 and 5=8, 13 and 3=10, 13 and 1=12, 13 and -1=14, 13 and -3=16, 13 and -5=18, 13 and -7=20, 13 and -9=22, 13 and -11=24, and as one stroke of the hammer corresponds to two teeth on the wheel r the clock will strike two, three, four, five, six, seven, eight, nine, ten, eleven, and twelve, 75 so respectively.

From the above it will be seen that from twelve to six o'clock the spring-actuated wheel r is rotated to the left $13 \times 6 = 78$ teeth, while the regulating mechanism of the striking-train has allowed the wheel r to turn 85 to the right only $2+4+6+8+10+12=42$ teeth. There is therefore a gain to the left of thirty-six teeth. During the time from six to twelve o'clock, however, the wheel r has again been turned $13 \times 6 = 78$ teeth to the left; but the striking mechanism has during this time allowed the wheel r to turn $14+16+18+20+22+24=114$ teeth to the right, a gain to the right of thirty-six teeth, which leaves the 90 wheel r in the position it was in at first. 95

The number of teeth on the wheel r is immaterial for striking the hour; but for the sake of details of construction as regards the arrangement of the steps on the snail n it is desirable that the wheel r should have at least 100 $11+9+7+5+3+1=36$ teeth.

To prevent an excessive tension of the spring of the spring-actuated wheel r when the hands are forcibly turned, it is judicious to limit the 105 amount to which the spring may be wound up. This is done by diminishing the thickness of two of the teeth of the spring-actuated wheel, or by bending them out of the plane of the wheel in such a manner that while they will 110 engage the teeth of the pinion d and turn the hammer they will not engage the teeth of the pinion l . In this case, however, the wheel r must have at least fifty-one teeth to admit the 115 thirty-six teeth gained to the left from twelve to six o'clock plus the thirteen which it is turned to the left from six to seven o'clock plus the two mutilated teeth.

In the arrangement above described the work of winding up is equally divided throughout the twelve hours, as far as the turning of the wheel r 13 teeth to the left is concerned; but the tension of the spring of the wheel r is somewhat increased during the time from 120 twelve to six o'clock, while it decreases the same amount from six to twelve o'clock.

The pinion d , instead of having two teeth, as above described, may have but one, and the pinion l will now be provided with seven instead of fourteen teeth. In this arrangement 125 one stroke of the hammer corresponds to one tooth of the spring-wheel; but to compensate for the gain to the left in this case during the time from twelve to six o'clock, it is neces-

sary to allow the spring-wheel to turn a little too much to the right every second hour, which is not practical.

The striking-train represented in Figs. 2^a and 2^b is in many respects so similar to that above described that a detailed description is unnecessary. The differences in the two arrangements are as follows: The spring-actuated wheel *r* in this case is a toothed sector, 10 and turns one tooth to the right at every stroke of the hammer; hence the pinion *d* in this case is provided with but one tooth. The toothed sector *r* is continually turned back to the left to the same position, whether one or more teeth have 15 been used during the striking, for the pinion *l* will turn the sector *r* back thirteen teeth every hour if it is allowed to engage it, while the sector *r* can turn to the right only twelve teeth at most at the end of an hour. The result 20 is that the pinion *l* engages the sector *r* uselessly after the last tooth of the sector to the right has come in contact with the pinion *l* until the toothless part of the pinion *l* is reached, when the sector *r* is allowed to turn to 25 the right and the striking begins. The escapement-lever *h* is here arranged horizontally, and generally rests, owing to its weight, on the pin *h*⁴. The lever *h* has now but one branch, *h*³, against which the tooth *s*² presses, 30 its purpose being to disengage the wheel *r* immediately before the striking begins in the same manner as explained before. The position of the striking-train represented by these Figs. 2^a and 2^b is as follows: The clock has 35 just struck two, and the T-shaped stopper *r*², fixed on the axle of the sector *r*, rests with the end *r*³ against the pin II of the snail *n*, mounted on the axle of the twelve-hour wheel of the center arbor. This snail is similar in principle to that before described, but in this case 40 it is somewhat differently arranged for the sake of giving space. The steps are here arranged in two groups, one consisting of the pins I to VI, inclusive, and the other of the steps or notches VII to XII, inclusive. The first group corresponds to the hours one to six, inclusive, and the second group to the hours seven to twelve, inclusive. The first group comes in contact with the end *r*³ of the 45 T-shaped stopper *r*², and the second group with the nose *r*⁴ at the other end of the head of the stopper *r*². In this case the snail *n* must be so arranged with reference to the T-shaped stopper *r*² that when the sector *r* has 50 been turned to the left by the pinion *l* as far as possible, and the pinion *l* has made a revolution and presented its toothless section to the sector *r*, and the snail has completed one-twelfth of a revolution, the sector *r* will now 55 be allowed to turn to the right a distance of three teeth before the end *r*³ of the stopper *r*² comes in contact with the pin III, and hence the clock will strike three. In the striking-train just described, however, an equal division 60 of the work of winding up, as described in the first arrangement, is not obtained; but this second arrangement is more simple and

more serviceable for many kinds of clocks. Arrangements first and second have this advantage in common: The striking-train is not 70 disarranged when the hands are forcibly turned—that is, the striking-train remains in accordance with the time-train.

Fig. 3^a represents a rear view of the striking-train in the second modification, and Figs. 3^b and 3^c plan views of portions of same. In this case the spring-actuated wheel *r* and the pinion *l* fixed to the same are loosely mounted on the axle *p*, and connected with said axle by a spiral spring. A wheel, preferably provided 75 with twice as many teeth as the center wheel and gearing with the center wheel, is mounted fixedly on the axle *p*. The axle *p* will therefore make six revolutions as often as the center wheel makes twelve—viz., every twelve 80 hours. The wheel *r* is now provided with thirteen teeth, and the striking-train so arranged that one stroke of the hammer corresponds to one tooth of the spring-actuated wheel. The wheel *r* will therefore make just 85 six revolutions to the right—viz., seventy-eight—the number of strokes the hammer makes during twelve hours, divided by thirteen, the number of teeth on its circumference or number of strokes corresponding to one 90 revolution. Thus the spiral spring which fastens the wheel *r* to the axle *p* receives a tension by the six revolutions of the axle *p* to the left sufficient to turn the wheel *r* six revolutions to the right, and hence gives the required 95 number of strokes. Furthermore, in this case, as in the first, an equal division of the work of winding up is obtained. To prevent an over-winding of the spiral spring by 100 forcibly turning the hands, it might be advisable to fix the axle end of the spring in the spring-box by friction only. The movement of the striking-train in this case is substantially the same as that shown in the first, with such modifications, however, as are required 105 in consequence of the vertical position of the hammer-axle. For the same reason the teeth on the wheel *r* are modified in form, as represented in Figs. 3^a and 3^c. The escapement-lever *h* is here represented as resting, owing 110 to its weight, on the fixed pin *h*⁴, and holds the wheel *r* from turning to the right by pressing against that tooth of the wheel *r* which is just on the point of turning to the right the tooth *d*' of the pinion *d*. The pinion *d* is here 115 mounted fixedly on the hammer-axle *a*, and hence the axle is turned to the right and the hammer *b* lifted from the bell whenever the pinion *d* is turned. In the position here represented the hammer has just struck, and the 120 escapement-lever *h* has been disengaged by the tooth *d*' in a manner similar to that before described. The wheel *r* now turns to the right, engages the tooth *d*', turns the pinion *d*, 125 disengages the lever *h*, and lifts the hammer from the bell ready for another stroke. The number of strokes is regulated in this case by the well-known circular plate *i*, which here 130 turns on a loose sleeve on the axle of the cen-

ter wheel. This circular plate is, as usual, provided with a division-rim, having teeth of different breadth and situated at different intervals, adapted to engage the tooth v' of the stopper-lever v , and this circular plate i is further provided with a rim having teeth adapted to engage with the teeth on the pinion l . The pinion l has thirteen teeth. The stopper-lever v rests with pin v' in a notch or interval of the division-rim, and with the tooth v^2 in a recess of the disk u , fixed on the hammer-axle a , whereby the hammer is held in the position represented. The striking-train is disengaged by means of the tooth t , fixed on the center-wheel axle which each hour lifts the lever $c c'$, pivoted at c^2 , causing the triangular tooth c^3 on the arm c' of the lever $c c'$ to press upward in the recess of the disk u , thereby removing the tooth v^2 of the stopper-lever v from said recess and pin v' from the interval on the division-rim, whereby the circular plate is free to turn. By this operation the striking-train receives only a start sufficient to place the tooth v^2 on the disk u , while the hammer is still held in position by the triangular tooth c^3 on the branch c' of the lever $c c'$. The hammer is disengaged only when the tooth t passes the branch c of the lever $c c'$. The moment this takes place the striking begins and continues until the tooth v' on the stopper v again drops into one of the intervals of the division-rim, and thus allows the tooth v^2 to engage the recess of the disk u .

Again, the spring-actuated wheel r may be mounted directly on the axle of the center wheel and turned by the same by means of a spring. In this case the circular plate is mounted on a separate axle of its own. The pinion l may then have six teeth and the tooth-rim of the circular plate seventy-two teeth, by which arrangement the same result is obtained as in the first case, provided that each stroke of the hammer corresponds to two teeth of the spring-wheel r .

From the above it will be seen that, by various combinations of the details above described, other arrangements of striking-trains may be constructed. In the arrangements shown by Figs. 1 and 2^a the hammer-axle may be arranged in a vertical position, while in the arrangement shown in Fig. 3^a a horizontal hammer-axle may be employed without requiring important modifications in construction.

The mechanism of the movement may also be arranged with various other combinations without departing from the spirit of my invention. Again, the winding-up mechanism may be arranged similar to a ratchet-drill, (ratchet-wheel and pawl,) the crank of which may be raised and lowered by means of an eccentric on the wheel-axle.

The spring of the hammer-axle should have the strength of a balance-spring of an ordinary watch. It is sufficient if the spring of the spring-actuated wheel r has a rigidity equivalent to that of two or three such balance-springs; hence it is clear that the power

required for the tension of the same, especially if the work of winding up is equally divided, is so insignificant that the loss of power in the spring or weight of the time-train used for this purpose has no influence on the movement of the clock. In fact, the resistance caused by the striking-train is so small that even watches may be provided with this arrangement, in which case, however, springs of corresponding strength must be used in all instances to produce the effect obtained by means of gravity in the above described arrangements.

Having fully described my invention, what I claim as new, and desire to secure by Letters Patent, is—

1. In a clock, the combination, with a time-train, of a striking-train located to one side of the central arbor or axle and in gear with a wheel on said arbor, whereby the striking-train is wound up.

2. In a clock, a striking-train wound by the actuating-power of the time-train, the said striking-train located to one side of the center axle or arbor and consisting of a winding-up mechanism composed of a pinion and spring-actuated wheel, a movement mechanism composed of a spring-actuated hammer, a ratchet-wheel, and escapement-lever, and a regulating mechanism composed of a snail-wheel, a stopper, and a wheel for regulating said stopper, substantially as set forth.

3. In a clock, the combination, with the time-train, of a striking mechanism wound by the actuating-power of the time-train, consisting of a mutilated pinion, a spring-actuated toothed wheel, an escapement-lever in connection with a disk and ratchet-wheel mounted on a hammer-axle, and said spring-actuated wheel, and a stopper in connection with a snail or other shaped wheel, substantially as set forth.

4. In a clock, the combination, with the time-train, of a striking-train, wound by the actuating-power of the time-train, consisting of a mutilated pinion mounted on the center arbor and adapted to engage and release hourly a spring-actuated wheel, a spring-actuated wheel adapted to store up and expend hourly a force sufficient to produce the required number of strokes, a snail-shaped wheel adapted to engage a stopper at required intervals, an escapement-lever adapted to engage a disk and said spring-actuated wheel, a ratchet adapted to allow said spring-actuated wheel to turn in one direction without engaging it and to engage it when it turns in the other direction, and a stopper adapted to arrest the motion of said spring-actuated wheel at required intervals, substantially as set forth.

5. In a clock, the combination of a toothed pinion mounted on the center arbor, said pinion adapted to engage a toothed spring-actuated wheel, a heart-wheel mounted on the center arbor and adapted to hold a stopper-lever at required elevations, a toothed spring-actuated wheel provided with a snail attachment,

5 said spring-actuated wheel adapted to be wound up by said pinion, and said snail attachment adapted to engage said stopper-lever at required intervals, an axle provided with a balanced hammer and circular disk, both mounted firmly thereon, a toothed pinion mounted loosely on said axle and loosely attached to said disk, an escapement-lever provided with a leaf and adapted to engage said disk and 10 said spring-actuated wheel, and a stopper-lever, the whole constructed and arranged for the purpose substantially as set forth.

15 6. In a striking-train for clocks, the combination of a spring-actuated hammer, a ratchet and escapement-lever adapted to arrest and release the movement of a spring-actuated wheel, a spring-actuated wheel adapted to store up and expend a sufficient amount of force to produce the required number of 20 strokes, a wheel and lever combinedly adapted to regulate the number of strokes, and a pinion located on the center arbor, adapted to wind up and release said spring-actuated wheel at regular intervals, the whole constructed, arranged, and adapted to be wound 25 by the actuating-power of the time-train, substantially as set forth.

7. In a striking-train for clocks, the combination, with the motive mechanism of the time-train, of a spring-actuated wheel forming a part of the striking-train, and located to one side of the center axle or arbor, and constructed and arranged to be wound up by said motive power the same amount each hour, and to reserve a sufficient force the first six 30 hours to balance the required expenditure of force the second six hours, substantially as set forth. 35

8. In a striking-train for clocks, the combination, with the motive-power mechanism of the time-train, of a mutilated pinion actuated by said motive power, constructed and arranged to engage a spring-actuated wheel forming a part of the striking-train, thereby winding up and releasing said spring-actuated wheel 40 at regular intervals, substantially as set forth. 45

In testimony whereof I have signed this specification in the presence of two subscribing witnesses.
